IGNITION SYSTEM FOR BURNERS

Arthur Stockstrom, Douglas D. Burnside, and Edwin H. Kahler, St. Louis, Mo., assignors to American Stove Company, St. Louis, Mo., a corporation of New Jersey

Application March 25, 1941, Serial No. 385,128

21 Claims. (Cl. 158—117.1)

This invention relates to an ignition system and pertains primarily and specifically to an electrical ignition system which has been conceived and designed for use in connection with gas ranges, but the principle of the invention is applicable to other specific uses wherein it is desired to electrically ignite a burner.

The primary object of the invention is the provision of a novel and highly efficient electrical ignition system for gaseous fuel burners and particularly burners of gas ranges.

Another object of the invention is the provision of an electrical ignition system which is semi-automatic in operation.

A still further object of the invention is the provision of an electrical ignition system having a timed cycle of operation and in which the timing of the cycle is accomplished by a circuit maker and breaker of novel construction and operation.

Other specific objects, novel features of construction and improved results of the invention will appear from the following description and the accompanying drawings in which an embodiment of the invention on a gas stove is illustrated.

In the drawings:

Fig. 1 is a horizontal sectional view through a gas range having the present improved invention applied thereto.

Fig. 2 is a detail fragmentary vertical sectional view through the flash tube, the pilot light burner and a portion of the main burner.

Fig. 3 is a horizontal sectional view through the circuit maker and breaker with the circuit open.

Fig. 4 is a horizontal sectional view through the circuit maker and breaker with the circuit closed.

Fig. 5 is a horizontal sectional view through the circuit maker and breaker at the moment the circuit is about to be opened and the parts returned to the positions illustrated in Fig. 3 of the drawings.

Referring now to the drawings, A designates a conventional insulated range oven and B an adjacent range compartment as is commonly found in ranges now in use.

Gas from any suitable source is supplied to the main fuel manifold pipe 1 from which delivery is under the control of any conventional type of gas valve 2 having exteriorly of the range body a manually operable valve opening and closing handle 3.

The range here illustrated is provided with automatic oven heat temperature control which

is effected by an oven heat regulator C the construction and operation of which is unnecessary to describe inasmuch as thermostatic oven temperature control is now commonly found in ranges and can be accomplished successfully and efficiently by any one of a number of oven heat regulating systems which can be bought on the open market. Obviously thermostatic control of the oven temperature could be eliminated without departing from the spirit of the present invention. Exteriorly of the range body the oven heat regulator is provided with a setting handle 4 and a temperature indicating dial 5.

15 The oven temperature regulator receives fuel from the gas cock through a pipe 6 and controls the discharge thereof through its outlet pipe 7 which leads into the oven chamber and is connected to a safety valve D.

20 An oven burner E having a conventional gas and air inlet manifold 8 is positioned within the oven and adjacent thereto is positioned a pilot light burner F.

The safety valve D need not be described in detail it being sufficient to state that the valve is biased to normally assume a closed position in respect to its gas outlet pipe 9 from which gas is delivered into the main burner inlet manifold 8 by a jet or fitting 10. The safety valve is 25 provided with a by-pass which when gas is delivered to the safety valve permits a small portion thereof to pass to the pilot light burner F through the by-pass pipe 11.

By reference to Fig. 2 of the drawings it will 30 be seen that the pilot light burner is provided with a burner jet 12 which burns one or more flames 13 which play upon and heat a thermal element 14 which is supported by and extends along the length of the pilot light burner housing. This thermal element when heated expands and has an end extending into the housing portion 15 of the safety valve and acts to 35 open said valve against its bias and permit gas to flow to the main burner E.

40 The main burner E is provided with a plurality of main burner ports 16 and is additionally provided with a chain of burner ports 17 which extend toward the pilot light burner and when fuel is admitted to the main burner and escapes from 45 the chain lighter ports 17 this fuel is ignited by the flame 13 of the pilot burner, which flame is burning by reason of the pilot light having been already ignited in a manner which will herein- 50 after be described, and upon being ignited burns as a series of flames 18 which perform the func-

tion of igniting the fuel which is escaping from the main burner ports 16 of the main burner E.

The pilot light burner jet is provided in its side with a burner orifice 19 aligned with the adjacent open end 20 of a flash tube G. This tube is supported upon the pilot light burner as indicated at 21 and is of considerable length and extends outwardly therefrom and has a remote open end 22 across which extends an ignition coil 23 carried by a block 24 which is properly apertured to telescopically receive the flash tube. Obviously the flash tube could be made of any desired shape in cross sectional configuration and the coil carrying block 24 will be composed of some suitable dielectric material.

The ignition coil 23 is connected in and forms a part of an electric circuit the nature of which will now be described. Current is brought to a transformer 25 by a pair of lead-in wires 26 and 27 which can be suitably connected to the ordinary lighting circuit of the building within which the range is located. It is immaterial whether or not the current supplied is alternating or direct in nature. From one side of the transformer a wire or conductor 28 is connected to a switch H the exact construction and operation of which will be hereinafter given. From the other side of the transformer a conductor 29 having therein a resistor 30 leads to and through a terminal block 31 and from this block to and through the ignition coil and back through the block over a wire 32 to the switch H. The switch H is provided with three terminals. The wire 28 is connected to the switch terminal 33, the wire 32 to the switch terminal 34, while a shunt wire 35 leading off of the wire 29 in front of the resistor is connected to the third switch terminal 36.

The switch or circuit maker and breaker H, as will be seen by reference to Figs. 3 to 5 of the drawings, comprises a base 37 of suitable dielectric material within which are the aforementioned terminals 33, 34 and 36. To this base is suitably secured a cover 38 to provide a closed housing or chamber 39. This switch box is mounted on or behind a front panel 40 of the range and is provided with a reciprocable push button 41 the end of which is externally positioned in respect to the range for convenient operation.

To facilitate the mounting of the switch box we provide a bushing 42 which extends through the range panel and in clamping the bushing to the panel between the lock nuts 43 and 44 we position a soft resilient washer 45 to prevent the panel, which ordinarily has an enameled exterior surface, from being chipped by reason of pressure exerted thereon by said lock washers.

The push button slides freely within the bushing and its inner end within the switch housing is provided with an enlarged head 46.

Within the housing a spring lever 47 has an end suitably secured as at 48 to the base block 37. This lever has an arm 49 having a normal bias toward the head of the push button so that it normally engages the same, as is illustrated in Fig. 3 of the drawings. The free end of this arm is bent backwardly upon itself as indicated at 50. The lever arm 49 carries a supplemental spring arm 51 to the end of which is suitably secured an electrical contact point or button 52. The spring lever 47 is electrically connected to the switch terminal post 33 as indicated at 53 and accordingly the electrical contact 52 is electrically connected to the current conducting wire 28.

Centrally of the housing a contact point or button 56 is arranged in approximate alignment with the contact button 52 and is carried on the end of a threaded bolt 57 which is electrically connected to the current conducting wire 32 through the switch terminal post 34. The threaded bolt 57 provides for adjustment of the contact button 56 toward and away from the contact button 52.

10 A second spring lever 58 has one end suitably anchored as at 59 to the switch base block 37 and has an arm 60 bent slightly back upon itself to provide an end arm 61 which is disposed at an inclination. This spring lever 58 has a bias in 15 the direction indicated by arrow which is toward the center of the switch housing with the result that when the switch button 41 is in its extended position the arm 61 of the lever 58 slightly overlies the arm 50 of the lever 47 and holds the arm 49 of the lever 47 in engagement with the head 53 of the push button and with the electrical contact button 52 in separated relationship in respect to the adjustable contact button 56.

The spring lever 58 is bi-metallic in nature so 25 as to constitute a thermally responsive element which upon being heated bows or moves into the opposite direction to its normal tension or bias or into the position illustrated in Fig. 5 of the drawings.

30 A resistance coil 62 is coiled about a portion of the bi-metallic spring lever 58 and electrically interconnects the current conducting wires 34 and 35 by having its ends electrically connected to the switch terminal posts 34 and 36 respectively.

35 It will be noted that the circuit is such as to be in parallel as respects the ignition coil and the resistance heater in the switch. With the resistor 30 in the circuit to the ignition coil less 40 current is delivered to the ignition coil than to the resistance heater in the switch. Should it be found desirable however the circuit could be arranged in series.

A few words should suffice to an understanding 45 of the operation of the invention. When the manual fuel valve 3 is opened fuel flows through the heat regulator to the safety valve and through the by-pass thereof to the burner orifices of the pilot light burner. The range operator then 50 manually pushes in upon the switch plunger 41 which brings the contact points 52 and 56 into engagement and the parts are locked in this position as illustrated in Fig. 4 of the drawings. The electric circuit is now closed through both 55 the ignition coil at the flash tube and also through the heating coil 62 in the switch. Gas is being discharged by the pilot light burner into the flash tube and this upon meeting the hot ignition coil explodes and flashes back and ignites the pilot burner. After a short time duration the heat from this burner causes the thermal element 14 to expand which results in an 60 opening of the safety valve D which permits gas to flow to the main burner. This gas issues from the chain lighter ports as well as the main ports of the main burner. The chain lighter ports are first ignited by the flame of the pilot burner and the flames burned by the chain lighter ports cause the ignition of the gas issuing from the 65 main burner ports. Throughout this cycle of operation the switch heater 62 has been heating the bi-metallic arm or lever 58 and shortly after the main burner becomes ignited this heat has caused the bi-metallic arm of the switch to warp 70 or move sufficiently to cause its arm 60 to clear 75

engagement with the contact carrying arm 49, as is illustrated in Fig. 5 of the drawings, and permit the arm 49 under its tension to move outwardly, pushing the push button 41 before it, and to assume a position where the contacts 52 and 56 become separated. The circuit is then broken and the parts are in the positions illustrated in Fig. 3 of the drawings where it will be seen that the arm 61 of the bi-metallic lever 58 prevents any accidental inward movement of the switch push button and thus guards against the circuit being accidentally closed.

The length of the cycle of time the circuit remains closed after being manually closed can be adjusted to meet the particular situation. This can be accomplished by using a bi-metallic arm or lever 58 which will deflect a larger or greater amount in accord with the heat applied thereto on a time basis or it can be varied by varying the heat output of the heating coil 62. It can also be varied by reducing or increasing the amount of overlap of the arms 49 and 60 which will increase or decrease the amount of deflection required of the bi-metallic arm in moving to an unlatched position.

The switch is such as to have the desirable feature of providing approximate uniform contact pressure between the contact points 52 and 56. This is by reason of the fact that the contact carrying arm 51 has a bias toward the fixed contact 56 so that when the contacts are brought into engagement the pressure between them remains practically constant notwithstanding the fact that the release or unlatching of the lever 49 is gradual until the end of its movement.

The switch also has the desirable feature that when the contact is finally broken it is by a snap-action because once the arm 60 of the bi-metallic lever 58 reaches a point where it is clear of the arm 49 this arm springs away towards its normal position carrying with it the contact 52. It will be seen too that as the switch is closed the arrangement of parts are such that it will snap to a closed position.

The switch cover 38 assures that the contact points and other operating parts of the switch are guarded against dirt and injury.

The invention is to be limited only within the scope of the hereinafter appended claims.

We claim:

1. An ignition system for a gas range or the like comprising, a main burner, a pilot burner for igniting said main burner, a manually operable valve for initially controlling the supply of fuel to both of said burners, a normally closed safety valve stopping the flow of fuel to the main burner from said manually operable valve, a thermo responsive member operable by the heat generated by said pilot burner to open said safety valve, an open electric circuit including an electric igniter in lighting relationship to the fuel issuing from said pilot burner, a switch by which said circuit can be closed, said switch including a fixed contact and a movable contact biased away from said fixed contact, means to move said contacts into engagement, a resilient lock arm automatically latching said contacts in engagement upon their being so positioned, said lock arm having a portion composed of thermo responsive material, an electric heater arranged in heating relationship to the thermo responsive portion of said lock arm, said heater being in said circuit, and said heater when said circuit is closed acting after a predetermined time duration to cause said lock

arm to move into an unlatched position, for the purpose described.

2. An ignition system for a gas range or the like comprising, a main burner, a pilot burner for igniting said main burner, a manually operable valve for initially controlling the supply of fuel to both of said burners, a normally closed valve stopping the flow of fuel to the main burner from said manually operable valve, a thermo responsive member operable by the heat generated by said pilot burner to open said safety valve, an open electric circuit including an electric igniter in lighting relationship to the fuel issuing from said pilot burner, a switch by which said circuit can be closed, said switch including a fixed contact and a movable contact carried by a resilient arm having a bias which maintains said contacts in separated relationship, a movable switch lever for moving said contacts into engagement, a resilient lock arm resiliently engaging said movable contact carrying arm and holding said arm in engagement with said movable switch lever, said lock arm moving beneath said movable contact carrying arm and holding the same against movement when said contacts are brought into engagement, said lock arm being thermally responsive, an electric heating coil in heating relationship with said lock arm and being in said electric circuit, and upon said electric circuit being closed said heater acting after a predetermined time to cause said lock arm to move out of engagement with said movable contact carrying arm to permit said arm to respond to its normal tension to move its contact away from said fixed contact.

3. An ignition system for a gas range or the like comprising, a main burner, a pilot burner for igniting said main burner, a manually operable valve for initially controlling the supply of fuel to both of said burners, a normally closed valve stopping the flow of fuel to the main burner from said manually operable valve, a thermo responsive member operable by the heat generated by said pilot burner to open said safety valve, an open electric circuit including an electric igniter in lighting relationship to the fuel issuing from said pilot burner, a switch by which said circuit can be closed, said switch including a fixed electrical contact, a spring arm in separated relationship to said fixed contact and having a bias in a direction away from said contact, a second resilient arm carried by said first named arm and having an electrical contact in said circuit, said second spring arm biased towards said fixed contact but normally in separated relation thereto, means to move said arms to bring said contacts into engagement, a resilient lock arm having a thermo responsive portion, said lock arm engaging said first named arm and locking the same against movement when the contacts have been brought into engagement, an electric heater in heating relationship to the thermo responsive portion of said lock arm and being in said electric circuit, and said electric heater acting after said circuit has been closed for a predetermined time to cause said lock arm to disengage said first named arm to permit said circuit to be broken in response to the movement under the normal tension of said first named arm.

4. An ignition system for a gas range or the like comprising, a main burner, a pilot burner for igniting said main burner, a manually operable valve for initially controlling the supply of fuel to both of said burners, a normally closed valve stopping the flow of fuel to the main burner from

said manually operable valve, a thermo responsive member operable by the heat generated by said pilot burner to open said safety valve, an open electric circuit including an electric igniter in lighting relationship to the fuel issuing from said pilot burner, a switch by which said circuit can be closed, said switch including a fixed electrical contact, a resilient movable arm carrying an electrical contact, the bias of said arm holding said contacts out of engagement, a resilient lock arm normally engaging said contact carrying arm and resiliently preventing movement of said arm to bring said contact into engagement, means to apply pressure to said contact carrying arm to move the same past said lock arm to cause said contacts to engage, the bias of said lock arm being such as to move said arm beneath said movable contact carrying arm to lock the same against movement when said contacts are in engagement, said lock arm being in the nature of a thermo responsive member movable to an unlocked position in respect to said contact carrying arm when heat is applied, an electric heater in heating relationship to said lock arm, said heater being in said electric circuit, and said electric circuit being closed to said heater when said contacts are brought into engagement.

5. A construction such as defined in claim 4 wherein, said thermo responsive lock arm is constructed to compensate against movement in response to ambient heat from said range.

6. A construction such as defined in claim 4 wherein, said electric igniter and said lock arm heater are connected in parallel in said circuit, and a resistor is in the circuit to said electric igniter.

7. An ignition system for a gas range or the like comprising a main burner, a pilot burner for igniting said main burner, a manually operable valve for initially controlling the supply of fuel to both of said burners, a normally closed valve stopping the flow of fuel to the main burner from said manually operable valve, a thermo responsive member operable by the heat generated by said pilot burner to open said safety valve, an open electric circuit including an electric igniter in lighting relationship to the fuel issuing from said pilot burner, a switch by which said circuit can be closed, said switch including a fixed contact and a movable contact biased away from said fixed contact, means to move said contacts into engagement, a lock member acting to automatically latch said contacts in engagement with one another after their having been so positioned, said lock member being thermo responsive, a heater arranged in heating relationship to said lock member, said heater being automatically brought into operation when said circuit is closed, and said lock member after a predetermined time interval responding to the heat generated by said heater and automatically moving into an unlatched position in respect to said movable contact.

8. An ignition system for a gas range or the like comprising, a main burner, a pilot burner for igniting said main burner, a manually operable valve for initially controlling the supply of fuel to both of said burners, a normally closed valve stopping the flow of fuel to the main burner from said manually operable valve, a thermo responsive member operable by the heat generated by said pilot burner to open said safety valve, an open electric circuit including an electric igniter in lighting relationship to the fuel issuing from said pilot burner, a switch by which said circuit

can be closed, said switch including a fixed electrical contact, a spring arm in separated relationship to said fixed contact and having a bias in a direction away from said contact, a second resilient arm carried by said first named arm and having an electrical contact in said circuit, said second spring arm biased towards said fixed contact but normally in separated relation thereto, means to move said arms to bring said contacts into engagement, a resilient lock arm having a thermo responsive portion, said lock arm engaging said first named arm and locking the same against movement when the contacts have been brought into engagement, a heater in heating relationship to the thermo responsive portion of said lock arm, said heater being automatically brought into operation upon the closing of said circuit, and said heater acting after said circuit has been closed for a predetermined time to cause said lock arm to disengage said first named arm to permit said circuit to be broken in response to the movement imparted to said first named arm due to the bias thereof.

9. An ignition system for a gas range or the like comprising a main burner, a pilot burner for igniting said main burner, a manually operable valve for initially controlling the supply of fuel to both of said burners, a normally closed valve stopping the flow of fuel to the main burner from said manually operable valve, a thermo responsive member operable by the heat generated by said pilot burner to open said safety valve, an open electric circuit including an electric igniter in lighting relationship to the fuel issuing from said pilot burner, a switch by which said circuit can be closed, said switch including a fixed electrical contact, a resilient movable arm carrying an electrical contact, the bias of said arm holding said contacts out of engagement, a resilient lock arm normally engaging said contact carrying arm and resiliently preventing movement of said arm to bring said contact into engagement, means to apply pressure to said contact carrying arm to move the same past said lock arm to cause said contacts to engage, the bias of said lock arm being such as to move said arm beneath said contact carrying arm to lock the same against movement when said contacts are in engagement, said lock arm being in the nature of a thermo responsive member movable to an unlocked position in respect to said contact carrying arm when heat is applied, a heater in heating relationship to said lock arm, and said heater being automatically brought into operation upon the closing of said electric circuit.

10. A construction such as defined in claim 2 wherein said electric heater is in the form of a coil coiled about said thermo-responsive lock arm.

11. In an ignition system for a gas range or the like, a main burner, a pilot burner for igniting said main burner, a valve for initially controlling the supply of fuel to both of said burners, a normally closed safety valve for stopping the flow of fuel to the main burner from said first named valve, an open electric circuit including an electric igniter in lighting relationship to the fuel issuing from said pilot burner, a thermo-responsive member operable by the heat generated by said pilot burner to open said safety valve, a switch by which said circuit can be closed, and means causing said switch to automatically open after said electric circuit has been closed for a predetermined length of time.

12. In an ignition system for a gas range or the like, a main burner, a pilot burner for ignit-

ing said main burner, a valve for initially controlling the supply of fuel to both of said burners, a normally closed safety valve for stopping the flow of fuel to the main burner from said first named valve, an open electric circuit including an electric igniter in lighting relationship to the fuel issuing from said pilot burner, a thermo-responsive member operable by the heat generated by said pilot burner to open said safety valve, a switch by which said circuit can be closed, and means brought into operation by the closing of said electric circuit causing said switch to automatically open after said electric circuit has been closed for a predetermined length of time.

13. An ignition system for a gas range or the like comprising a main burner, a pilot burner for igniting said main burner, a manually operable valve for initially controlling the supply of fuel to both of said burners, a normally closed valve stopping the flow of fuel to the main burner from said manually operable valve, a thermo-responsive member operable by the heat generated by said pilot burner to open said safety valve, an open electric circuit including an electric igniter in lighting relationship to the fuel issuing from said pilot burner, a switch by which said circuit can be closed, said switch including a fixed contact and a movable contact biased away from said fixed contact, means to move said contacts into engagement, a lock member acting to automatically latch said contacts in engagement with one another after their having been so positioned, thermo-responsive means for moving said lock member to an unlatched position, a heater arranged in heating relationship to said lock operating thermo-responsive means, and said heater being automatically brought into operation when said circuit is closed and the heat generated thereby causing said lock member to be moved into an unlatched position in respect to said movable contact after a predetermined time interval.

14. A construction such as defined in claim 13 wherein, said thermo-responsive lock operating means is constructed to compensate against movement in response to ambient heat from said range.

15. A construction such as defined in claim 13 wherein, said heater is an electric heater and is in the form of a coil coiled about said lock operating thermo-responsive means.

16. An ignition system for a gas range or the like comprising, a main burner, a pilot burner for igniting said main burner, a manually operable valve for initially controlling the supply of fuel to both of said burners, a normally closed valve stopping the flow of fuel to the main burner from said manually operable valve, a thermo-respon-

sive member operable by the heat generated by said pilot burner to open said safety valve, an open electric circuit including an electric igniter in lighting relationship to the fuel issuing from said pilot burner, a switch by which said circuit can be closed, said switch including a fixed contact and a contact carried by a movable arm which is biased to maintain said contacts in separated relationship, means for moving said contacts into engagement, a lock arm biased to engage said movable contact carrying arm to hold the same against movement when said contacts are brought into engagement, thermo-responsive means for moving said lock arm against its bias, a heater for heating said thermo-responsive means and being brought into operation when said electric circuit is closed, and the heat generated by said heater acting after a predetermined time to cause said thermo-responsive means to move said lock arm out of engagement with said movable contact carrying arm to permit said arm to move its contact away from said fixed contact.

17. A construction such as defined in claim 7 wherein, said thermo-responsive lock member is constructed to compensate against movement in response to ambient heat from said range.

18. A construction such as defined in claim 7 wherein, said heater is an electric heater arranged in said electric circuit, and said electric igniter and said electric heater are connected in parallel in said circuit.

19. A construction such as defined in claim 12 wherein, the means causing the opening of the switch is thermo-responsive in nature and is caused to actuate by the heat from a heater brought into operation by the closing of said electric circuit.

20. A construction such as defined in claim 12 wherein, the means causing the opening of said switch is a thermo-responsive means, and an electric heater is provided in said electric circuit for generating the heat for causing the operation of said thermo-responsive means after said circuit has been closed for a predetermined length of time.

21. A construction such as defined in claim 12 wherein, the means causing said switch to automatically open is a thermo-responsive means, an electric heater in said electric circuit, and said heater being in the form of a coil coiled about said thermo-responsive means to heat the same to cause the operation thereof after a predetermined length of time.
